UNITED STATES PATENT OFFICE.

HUGH W. KIMES, OF DAYTON, OHIO, ASSIGNOR TO THE VAILE-KIMES COMPANY, OF DAYTON, OHIO, A CORPORATION OF OHIO.

AUTOMATIC CUT-OUT FOR ELECTRIC MOTORS.

1,195,232.

Specification of Letters Patent. Patented Aug. 22, 1916.

Application filed June 18, 1915. Serial No. 34,494.

To all whom it may concern:

Be it known that I, HUGH W. KIMES, a citizen of the United States, residing at Dayton, in the county of Montgomery and State of Ohio; have invented certain new and useful Improvements in Automatic Cut-Outs for Electric Motors, of which the following is a specification, reference being had therein to the accompanying drawing.

This invention relates to automatic cut-outs for electrical motors and more particularly to a pressure controlled cut-out for the motor of a pump used in connection with a water distribution system in which the water is stored in a tank under air pressure, which pressure serves to distribute the same through the system.

The object of the invention is to provide a device of this kind which will positively break and make the circuit and in which the contact member will be moved quickly out of contact with and away from its coöperating contact member so that there will be little or no sparking and no burning of the contacts.

It is also an object of the invention to provide a device of this kind which will be simple in its construction and operation, thereby enabling it to be manufactured and marketed at a comparatively low cost and simplifying the upkeep of the same.

In the accompanying drawings, Figure 1 is a side elevation of a device embodying my invention; Fig. 2 is a vertical sectional view of the same taken just inside one of the frame members; Fig. 3 is an end elevation showing the contact members, partially broken away to show the stops; and Fig. 4 is an elevation of that end of the device opposite that shown in Fig. 3, partially broken away and showing the controlling lever.

In these drawings I have illustrated one embodiment of my invention and have shown the same as comprising a base 1 having therein a chamber comprising a fixed lower wall 2 and a flexible upper wall 3, which constitutes a diaphragm. This chamber is connected by means of a conduit 4 with the pressure tank so that the diaphragm is subjected at all times to the pressure of the air within the tank. Rigidly secured to the base and extending upwardly

therefrom are two frame members 5 connected at their upper ends by a cross member 6. In the present instance the frame members and base are cast integral but obviously they may be united in any suitable manner. Arranged between the side members of the frame is a plunger 7 having at its lower end an enlarged portion or base 8 which extends through an opening 9 in the base 1 of the frame and rests upon the diaphragm 3. The upper end of this plunger extends through an opening in the top member 6 of the frame. Coiled about the plunger is a spring 10 which is confined between the shoulder 11 near the lower end thereof and the top wall of the frame. Preferably, the top wall is provided with an adjustable part, such as a screw plug 12, having an opening to receive the upper end of the plunger and having its lower end in engagement with the spring 10 to regulate the tension thereof. The tension of the spring 10 is such that it prevents the upward movement of the plunger until the pressure in the tank and in the chamber beneath the diaphragm 3 reaches a certain predetermined point. When the pressure exceeds this predetermined point the spring will yield and permit the plunger to move upward and it will be retained in its upper position until the pressure falls sufficiently to permit the spring to move the plunger downward.

Mounted upon the frame are suitable contact members, and, in the present instance, we have shown these contact members as comprising a pair of fixed contacts 13 mounted on a block of insulating material 14, which is secured to the frame of the device, and having binding posts 15 by means of which they may be connected in an electrical circuit. Coöperating with the fixed contact members is a movable contact member 16 which is here shown as bifurcated and having separate but connected arms to engage the respective fixed contact members. Preferably, the several contact members are provided with contact points 17. A suitable actuating device is provided for moving the movable contact member 16 into and out of engagement with the fixed contact member and, in the present arrangement of the mechanism, the movable contact mem-

ber is secured to and carried by this actuating device. This, however, is an optional arrangement. As here illustrated the actuating device comprises an arm 18 pivotally mounted on studs 19 at the upper corner of the frame opposite the plug 12. This arm is provided with a depending portion 20 to which is secured a block 21 of insulating material, to which, in turn, is secured the movable contact member 16. Movable mounted upon the frame and operatively connected with the plunger 7 is a controlling device by means of which the actuating device for the movable contact is caused to move that member in a direction to make or break the circuit as may be required by the condition of the pressure in the tank. As here shown, this controlling device comprises a bifurcated lever 22 having its arms straddling the plunger 7 and pivotally connected to the lower corner of the frame diagonally opposite the axis of the actuating device 18. The arms of the controlling member are connected one to the other at a point remote from the axis of that member and the end of the controlling member is arranged to coöperate with the actuating device, as will be hereinafter explained. The controlling device may be connected with the plunger in any suitable manner. In the present instance it is provided with a projection or lip 23 extending into a slot 24 in the lower portion of the plunger and preferably provided with an antifriction roller 25 which engages the walls of the slot. Thus, it will be apparent that the rising and falling movement of the plunger will be transmitted to the controlling lever. The movement of the controlling lever is limited by means of stops 26 and 27 arranged below and above, respectively, the free end of the lever and preferably cast integral with one of the side members of the main frame. As has been stated the actuating device and the controlling device coöperate to cause the movement of the movable contact member and one of these devices, preferably the actuating device, is provided with a yieldable part having converging surfaces adapted to engage different portions of the other device, in the present instance, the controlling device, as the controlling device is moved into different positions. This yieldable part of the actuating device is so arranged with relation to the axis of that device that when one of its surfaces is in engagement with the controlling device the actuating device will be moved in one direction and held against movement in the other direction until the controlling device has changed its position so as to permit the other surface of the yieldable part of the device to engage the same. The engagement of this second surface of the yieldable part with the control-

ling member will cause the actuating device to be moved in the opposite direction and held against return movement until the controlling member again moves into its first position.

The parts may be of various kinds and variously arranged but, in the present instance, the actuating device or arm 18 has a laterally extending portion 28 to which is pivotally connected one end of a lever 29 which extends transversely to the arm and has a tapered nose 30, the converging sides or surfaces of which extend beyond the lower edge of the arm, which is bifurcated to receive the lever. The arm is provided with a radially extending socket or recess in which is mounted a spring 33 which is confined between the end of the socket and the arm 29 and serves to hold the nose 30 yieldably in engagement with the end of the controlling lever. The apex of this tapered nose is arranged parallel with the axes of the arms and the tapered surfaces thereof are arranged on opposite sides of a line extending through the axis of the actuating arm and the controlling lever. The upper end of the controlling lever is so arranged with relation to this line that it will move from one side to the other thereof. The spring 33 is also arranged to exert its force and to be compressed in a direction extending substantially lengthwise of this line, as shown. Further, the tapered nose is so arranged with relation to the end of the lever that it will bear constantly upon the same. With the parts in the positions shown in Fig. 2 the circuit is broken and the pressure under the diaphragm is holding the plunger and the controlling device in their uppermost positions. As soon as this pressure falls below a predetermined point the controlling lever will begin to move downward, that is, toward the stop 26. As it moves it will force the yieldable part 30 of the actuating device toward the axis of that device but the pressure will be in a direction to hold the device in its present position against the stop 26 with which it engages, as will be described, with the contacts separated. The instant the end of the controlling lever passes the apex of the tapered nose the other surface of the latter will engage the end of the controlling lever and the pressure will be in a direction to move the actuating arm about its axis in a direction to close the contacts. It will be noticed that either one side or the other of the nose 30 will exert a pressure against the end of the lever 22 according to the position of the lever, this pressure being due to the compression of the spring 33. This results in the nose being cammed to one side or the other, accordingly carrying with it the pivoted arm to which it is attached. It will be noted that this movement of the actuating

device takes place instantly upon the passing of the controlling lever and regardless of the further movement of the controlling lever. The controlling lever is provided in 5 its outer end with a roller 31 with which the tapered nose 30 of the actuating arm engages and which has not only the usual functions of an anti-friction roller but also serves to prevent the apex of the nose from hanging 10 on the end of the roller. The actuating device or arm is provided with a laterally extending stop 32 which is arranged between and cooperates with the stops 26 and 27 to limit the movement of the actuating device 15 about its axis and to hold the same immovable during the compression of the spring 33 and the initial movement of the controlling device. Preferably, the apparatus as a 20 whole is inclosed in a cylindrical casing 34 which is removably mounted on the base 1.

The operation of the apparatus will be fully understood from the foregoing description and it will be apparent that the 25 operation of the movable contact member is quick and positive. As the controlling device moves from one position to another the actuating device is not moved but is retained in its position until the controlling device passes a central point and then the 30 spring of the actuating device causes the same to move about its pivotal center and thus impart movement to the contact member. Further, the device is very simple in its operation and in its construction. Consequently, it is not liable to become disarranged or broken in operation and has no delicate adjustments which must be made and maintained. Further, the simplicity of 35 its construction enables it to be manufactured at a low cost. The base and main frame constitute a single casting and there are but few other parts and these parts are of such a character that they require but little machine work.

45 While I have shown and described one embodiment of the invention it will be understood that this has been chosen for the purposes of illustration only, and that I do not desire to be limited to the details of construction shown and described except as required by the scope of the claims, for obvious modifications will occur to a person skilled in the art.

Having thus fully described my invention, what I claim as new and desire to secure by Letters Patent, is:—

50 1. In a device of the character described, contact members, one of which is movable, an actuating device for said movable contact member comprising a movable member and a spring-controlled part provided with converging surfaces constituting cams, and a controlling device comprising a pivoted lever arranged to move from one cam surface to the other across the converging ends

thereof, said spring normally exerting a force to move said part toward the lever, whereby the movement of the lever from one surface to the other first tensions the spring and then causes the part to exert a cam 70 action against the lever to actuate the movable member.

2. In a device of the character described, fixed and movable contact members, an actuating device for said movable contact member comprising a movable member and a spring controlled part mounted thereon and provided with converging surfaces constituting cams, a pivoted controlling lever arranged to move from one cam surface to the other across the converging ends thereof, said spring normally exerting a force to move said part toward the controlling lever, whereby the movement of the latter from one surface to the other first tensions the 80 spring and then causes the part to exert a cam action against the controlling lever to actuate the movable member, and stops to definitely limit the movement of the controlling lever in both directions.

3. In a device of the character described, contact members, one of which is movable, an actuating device for said movable contact member comprising a movable member and a spring-controlled pivoted part provided with converging surfaces constituting cams, and a controlling device comprising a pivoted lever arranged to move from one cam surface to the other across the converging ends thereof, said spring normally exerting a force to move said part toward the lever, whereby the movement of the lever from one surface to the other first tensions the spring and then causes the part to exert a cam action against the lever to actuate the movable member.

4. In a device of the character described, contact members, one of which is movable, a pivoted actuating device for said movable contact member, a pivoted controlling device comprising a lever having an end extending toward said actuating device, said actuating device comprising a part having cam surfaces converging to an edge adjacent a line drawn through the said pivots and in contact with the end of said lever, and a spring arranged to normally exert a force lengthwise of said line and thereby pressing said part against the end of said lever, the arrangement being such that when the said lever is initially moved it will move said part, thereby compressing the spring, and then the said part will exert a cam action against the said controlling lever, thereby shifting the actuating device.

5. In a device of the character described, contact members, one of which is movable, an actuating device for such movable contact member comprising a spring-actuated part moving said actuating device, a con-

- trolling device arranged to engage different portions of said spring-actuated part, and stops on opposite sides of said actuating device and said controlling device limiting the movement thereof in both directions to hold said actuating device against movement during the engagement of said controlling device with one portion of said part and to hold said controlling device against movement during its engagement with the other portion of said part.
6. In a device of the character described, fixed and movable contact members, an actuating device for said movable contact member comprising a pivoted member and a transversely extending lever pivoted thereto on an axis remote from the pivot of said member and provided with a tapered nose, a spring acting on said lever to move the same away from the axis of said member, and a controlling device having a part adapted to be engaged by different sides of said tapered nose when said controlling device is in different positions.
7. In a device of the character described, a main frame, a fixed contact carried by said main frame, an actuating device pivotally mounted on said frame, a movable contact operated by said actuating device, a controlling device comprising a lever pivotally mounted on said frame at a point remote from said actuating device and having an end extending toward the same, said actuating device comprising a spring-pressed part having converging surfaces arranged on opposite sides of a line drawn through the pivots of said devices, said surfaces being adapted to exert a cam action against the end of said lever when the latter is moved into different positions, whereby said actuating device is moved in one direction or the other.
8. In a device of the character described, a main frame; a fixed contact carried by said main frame, an actuating device pivotally mounted on said frame, a movable contact operated by said actuating device, said actuating device comprising a spring-pressed part movable relatively thereto and having converging surfaces, a controlling device pivotally mounted on said frame, and a roller carried by said controlling device and adapted to be engaged by different surfaces of said movable part when said controlling device is in different positions, whereby the action of said spring will cause said actuating device to be moved in different directions.
9. In a device of the character described, a main frame, a fixed contact carried by said main frame, an actuating device pivotally mounted on said frame, and a movable contact operated by said actuating device, said actuating device comprising an arm having a recess, a pivoted lever extending transversely to said recess, and a spring mounted in said recess and tending to move said lever away from the axis of said arm, said lever having a tapered nose arranged with its apex extending substantially radially of said actuating device, and a controlling device adapted to be engaged by different sides of said tapered nose when said controlling device is in different positions.
10. In a device of the character described, contact members, one of which is movable relatively to the other, a pivoted actuating device for said movable contact member comprising an arm having a longitudinal recess, a pivoted lever extending transversely to said recess and having a tapered nose, and a spring mounted in said recess and acting on said lever to move the same away from the axis of said device, and a controlling device having a part adapted to be engaged by different sides of said tapered nose when said controlling device is in different positions.
11. In a device of the character described, contact members, one of which is movable relatively to the other, an actuating device for said movable contact member comprising a spring-actuated part having converging surfaces, a controlling device having a part arranged to be engaged by different surfaces of said spring-actuated part when said controlling device is in different positions, and means on each side of the controlling device to definitely limit the movement of the same in both directions.
12. In a device of the character described, contact members, one of which is movable relatively to the other; an actuating device for said movable contact member comprising a spring-actuated part having converging surfaces, a controlling device having a part arranged to be engaged by different surfaces of said spring-actuated part when said controlling device is in different positions, and a single pair of stops arranged on opposite sides of said devices to limit both movements of said actuating device and of said controlling device.
13. In a device of the character described, a frame, a fixed contact member carried by said frame, an actuating device pivoted at one of the corners of said frame, a movable contact member operated by said actuating device, said actuating device comprising a spring-actuated part having converging surfaces, a laterally extending lug carried by said actuating device, a controlling lever pivotally mounted at that corner of said frame diagonally opposite the axis of said actuating device, extending toward said actuating device and having a part arranged to be engaged by different surfaces of said spring-actuated part of said actuating device when said lever is in different positions, and lugs extending inwardly from said

frame and arranged in the paths of said lever and of said lug on said actuating device.

14. In a device of the character described, 5 contact members, one of which is movable, an actuating device for said movable contact member comprising a pivoted member and a spring-controlled part mounted there-

on and provided with converging cam surfaces, a pivoted controlling lever adapted to 10 engage the cam surfaces, and stops arranged in the paths of said pivoted member and controlling lever.

In testimony whereof I affix my signature.

HUGH W. KIMES.
